UNITED STATES PATENT OFFICE.

HENRY A. WISE WOOD, OF NEW YORK, AND JOHN A. ISBELL, OF MIDDLETOWN, NEW YORK, ASSIGNEES, BY MESNE ASSIGNMENTS, TO WOOD NEWSPAPER MACHINERY CORPORATION, OF NEW YORK, N. Y., A CORPORATION OF VIRGINIA.

FOLDING-BLADE-ADJUSTING MECHANISM.

1,213,325.

Specification of Letters Patent. Patented Jan. 23, 1917.

Application filed June 5, 1913, Serial No. 771,854. Renewed June 29, 1916. Serial No. 106,739.

To all whom it may concern:

Be it known that we, HENRY A. WISE WOOD and JOHN A. ISBELL, citizens of the United States, said WOOD residing at New York, county and State of New York, and said ISBELL residing at Middletown, in the county of Orange and State of New York, have invented a new and useful Folding-Blade-Adjusting Mechanism, of which the following is a specification.

This invention relates to improvements in the folding cylinders employed in modern high speed web printing machines.

The principal object of the invention is to provide practicable means whereby the folding blades can be adjusted on the folding cylinder toward and from the point thereon at which the web is cut. Thus the adjustment can be effected without adjusting or disturbing the cutting cylinder or either member of the cutting mechanism carried by the cutting and folding cylinders.

Another object of this invention is to provide for accomplishing this result in a simple and expeditious manner without adding any material complications to the folding cylinder or materially increasing the cost thereof.

The invention also involves improvements in details of construction and combinations of parts as will appear hereinafter.

Reference is to be had to the accompanying drawings in which—

Figure 1 is an end elevation of a folding cylinder with parts in section, the adjacent members of the folding and cutting mechanism being shown in dotted lines, and Fig. 2 is a sectional view of the same on the line 2—2 of Fig. 1.

The invention is shown as applied to a folding cylinder 1 which co-operates with the cutting cylinder 2 and folding rolls 3. The cutting mechanism comprises the usual blade 5 carried by the cutting cylinder and in this case, two co-operating members 6 carried by the folding cylinder. Each of these members 6 is provided with a rubber pad 7.

Each end of the folding cylinder is provided with an annular recess 10. In each one is located a bearing plate 11 of circular form. These plates are capable of being adjusted circumferentially in the recesses 10 relative to the members 6 and pads 7. For the purpose of holding these plates 11 in

their adjusted positions, they are provided with circumferentially elongated perforations 14 for receiving bolts 15, which screw into the cylinder and hold the bearing plates in position as adjusted. Each of these bearing plates is provided with housings 16 between which are located bearings 17, those shown in the drawings being of the ball bearing type. In these bearings are mounted the folding blade shafts 18, which otherwise are constructed in the usual way. The folding blades 20 are mounted on these shafts and co-operate with the folding rolls 3 as usual. The cylinder is provided with a series of slightly elongated clearance holes 21 for the blades, which permit the adjustment. When on account of a change in the character of the work, or for any other reason, it is found that the fold does not come exactly in the center of the sheet, adjustment can be made by loosening the bolts 15, and shifting the two bearing plates 11 toward or from the corresponding pad 7 until the desired position is reached. Then the plates are clamped in their adjusted positions by tightening up the bolts 15. In this way accurate folding is possible under all conditions and the equal adjustment of both folding blades is secured without disturbing the relative adjustment of the two members of the cutting mechanism.

Although we have illustrated and described only a single embodiment of the invention, we are aware of the fact that many modifications can be made therein by any person skilled in the art without departing from the scope of the invention as expressed in the claims. Therefore we do not wish to be limited to the details of construction herein shown and described, but

What we do claim is:—

1. The combination with a folding cylinder having a cutting member thereon and provided with recesses therein, of bearing plates circumferentially adjustable in said recesses toward and from said cutting member, and a folding blade shaft supported by said bearing plates.

2. The combination with a folding cylinder having annular recesses in its ends opposite each other, circular bearing plates located in said recesses and adjustable there-in circumferentially of the cylinder, bearings located in said plates, a shaft rotatable in

3
said bearings, and a folding blade mounted on said shaft.

3. The combination with a folding cylinder having annular recesses in its ends, circular bearing plates located in said recesses and adjustable therein circumferentially of the cylinder, means for clamping said plates to the cylinder in their adjusted positions, ball bearings in said plates, a shaft rotatable in said bearings, and a folding blade mounted on said shaft.

4. A folding cylinder having in combination a cutting member mounted on said cylinder, a pair of cylinder ends each provided with an annular recess therein, circumferentially slotted plates mounted in said re-

cesses, bolts in said slots for securing said plates in adjusted angular position, two sets of diametrically opposed bearings in said plates, a shaft rotatable in each set of bearings, and a folding blade on each shaft, angular adjustment of the plates being effective to vary the angular relation of the shafts and the cutting member.

In testimony whereof we have hereunto 25 set our hands, in the presence of two subscribing witnesses.

HENRY A. WISE WOOD.
JOHN A. ISBELL.
